UNITED STATES PATENT OFFICE

OTTO H. L. THELEN, OF LYNN, MASSACHUSETTS

SHOE AND SHANK STIFFENER THEREFOR

Application filed February 16, 1928. Serial No. 254,653.

It has been customary to reinforce the shank portions of shoes with stiffening strips, usually of metal, extending from the heel portions along the shanks to approximately the 5 break line of the shoe, often slightly forwardly of this line. When the heels are very high a very considerable stress is placed on these stiffeners during use and as heretofore constructed there has been considerable trouble 10 from breakage of the stiffeners in high heeled shoes about in line with the forward edges of the heels. In the case of a McKay shoe the stiffener must be quite narrow at the narrowest part of the shank in order to clear 15 the needle of the McKay stitcher.

The present invention has for its chief object the production of a shoe stiffener considerably stronger than now commonly used but which is sufficiently narrow at the narrow- 20 est part of the shoe shank to permit it to be used in McKay as well as in shoes of other types and which it is unnecessary to extend forwardly of the break line.

For a more complete understanding of this 25 invention, reference may be had to the accompanying drawings in which

Figure 1 is a perspective of the stiffener particularly suitable for use in a McKay shoe.

Figure 2 is a fragmentary top plan of the shoe, the sock lining being removed, showing the position of the stiffener with relation to the McKay stitching.

Figure 3 is a fragmentary central longitudinal section through a McKay shoe showing the stiffener in position.

Figure 4 is a detail section on line 4—4 of Figure 3.

Figures 5 and 6 are sections somewhat similar to Figure 4 but showing a turn and a welt shoe, respectively.

Referring to Figure 1 it will be seen that the stiffener comprises a strip of metal 1 which is molded longitudinally to the longitudinal curvature of the shank. Intermediate 45 its ends this strip is provided with a stiffening rib 2, its side portions 3 merging with flat portions 4 and 5 at the forward and rear ends of the rib 2. The marginal portions 3 are of greatest width adjacent to the rear end

portion of the rib 2 as at 7 and taper in width to the narrowest portion at the point 6 toward the forward end of the stiffener. This narrowest portion, when the stiffener is in a shoe, is positioned substantially at the narrowest portion of the shank as at 8 where the lines of McKay stitching 9 (see Figure 2) approach nearest to each other. Rearwardly of this point the stitches diverge and the total width of the shank stiffener may thus be increased toward the heel end of the shoe without coming sufficiently close to the McKay stitches to cause liability of the McKay needle striking the stiffener. It will be seen that the shank stiffener, being 55 tapered, is somewhat wedge shape and that its outer edges closely parallel the lines of the McKay stitching from the heel portion forwardly to their points of least spacing. Pressure exerted on the intermediate portion 70 of the stiffener, as by the weight of the wearer, thus tends to wedge the shank piece more tightly in position against the edges of the upper material inwardly of these stitch lines, holding the stiffener from longitudinal slipping and relieving the end fastenings, as later described, from some of the load which otherwise would be imposed thereon. Also 75 since the stitches come close to the edge of the stiffener the showing of ridges on the outer face of the outersole at the edges of the stiffener is prevented. As the stiffener is symmetrical on opposite sides of its longitudinal axis the same stiffener is applicable to either right or left shoes. Heretofore it has 80 been usual practice to extend the stiffener forwardly of the break line of the sole in order to afford a bearing for the stiffener on the forepart of the sole in an attempt to counteract to some extent the tendency of the stiffener to move forwardly due to the weight 85 of the wearer. This, however, stiffens the shoe sole at about the break line which is not desirable in high heel shoes as it interferes with the natural flexing of the foot in walking and causes the shoe to be uncomfortable. Moreover, it is not wholly effective in holding the stiffener back in the position where it 90 belongs.

The rear end of the stiffener back of the 100

point 7 is shown as narrowed so as to avoid interference with the attaching nails when wood heels are used and forms a flat plate portion at 16 which may be provided, if desired, with means by which the stiffener may be fixed in the shoe. Any suitable means may be employed but as shown the fastening means comprises a pair of prongs 11 formed by striking material from the portion 16 in opposite directions, these prongs being driven into the adjacent sole member. At the forward end the stiffener may be provided with attaching means, and as herein shown these comprise the prongs 12 similar to the prongs 11. Where the stiffener is to be used in a McKay shoe these prongs are downwardly extended in order that the stiffener may be fixed to the outersole. In the case of turns and welts they would ordinarily be struck upwardly in order to be fixed to the innersole or shank piece, respectively.

The widest portion of the stiffener at the point 7 comes substantially in line with the forward edge of the heel 15, as shown in Figure 3, thus providing the greatest amount of metal at this point where breakage is most likely to occur, while the forward portion of the stiffener is so narrow that it may lie sufficiently inwardly of the McKay stitches to be used satisfactorily in a McKay shoe.

Preferably, particularly when used for McKay work, these stiffeners are formed initially straight longitudinally, but with the longitudinal stiffening rib, and are then molded to longitudinal curvature simultaneously with the molding of the sole members to which they are attached, this general method being that described and claimed in the Bartels Patent No. 1,619,648, granted March 40, 1927.

As shown in Figure 4, the stiffener lies between the inner sole 20 and the outersole 21 of the McKay shoe between the stitch lines 9. When used in a turn shoe the stiffener is fixed 45 to the shank piece, as shown at 22 in Figure 5, and lies between its lower face and the upper face of the turn sole 23. In the case of the welt shoe the stiffener is fixed to the innersole 25 and lies between this and the outer sole 26.

From the foregoing description of certain embodiments of this invention, it should be evident to those skilled in the art that various changes and modifications may be made 55 without departing from the spirit or scope of the invention as defined by the appended claims.

I claim:

1. A shoe shank stiffener comprising a rigid metal strip symmetrical about a longitudinal axis and molded lengthwise to the desired contour and having a central longitudinally extending stiffening rib formed by opposite side portions, said ridge forming side portions being of greatest width adjacent

to the rear end of the stiffener and narrowing toward its forward end, the forward end of said stiffener terminating at least as far back as the break line of the sole.

2. A shoe shank stiffener comprising a rigid metal strip molded lengthwise to the desired contour and having a central longitudinally extending stiffening rib formed by opposite sides which merge with flat portions at the ends of said rib, said sides being of greatest width toward the rear end of the stiffener and narrowing toward its forward end and symmetrical on opposite sides of its central longitudinal axis, and said end portions being constructed for rigid attachment to a shoe sole member, the forward end of said stiffener terminating at least as far back as the break line of the sole.

3. A shoe of the McKay type having inner and outersoles, upper materials having their margins extended between said soles and secured thereto by lines of McKay stitches converging forwardly of the heel breast, and a shank stiffener between said inner and outersoles and said margins bent laterally along a median line with its concave face adjacent to said innersole, the side edges of said stiffener converging forwardly of the heel breast and closely paralleling the lines of McKay stitching, whereby pressure exerted upon the intermediate portion of the stiffener tends to wedge the stiffener more tightly in place against the edges of the upper and hold it from longitudinal slipping.

4. A shoe of the McKay type having inner and outersoles, upper materials having their margins extended between said soles and secured thereto by lines of McKay stitches converging forwardly of the heel breast, and a shank stiffener between said inner and outersoles and margins, the side edges of said stiffener converging forwardly of the heel breast and closely paralleling the lines of McKay stitching, whereby pressure exerted upon the intermediate portion of the stiffener tends to wedge the stiffener more tightly in place against the edges of the upper and hold it from longitudinal slipping.

In testimony whereof I have affixed my signature.

OTTO H. L. THELEN.
